(57) **CLAIM**

The ornamental design for a rollable and motorized door for vehicle shelter, as shown and described.

DESCRIPTION

FIG. 1 is a perspective view of a rollable and motorized door which is mounted on a vehicle shelter, the door comprising a sheet with lateral bulges and the door being in a wound position;

FIG. 2 is a front view of the rollable and motorized door which is mounted on the vehicle shelter shown in FIG. 1; FIG. 3 is a rear view of the rollable and motorized door which is mounted on the vehicle shelter shown in FIG. 1; FIG. 4 is a right side view of the rolled and motorized door that is mounted to the vehicle shelter shown in FIG. 1;

FIG. 5 is a detailed perspective view of the left side of the rollable and motorized door which is mounted on the vehicle shelter shown in FIG. 1;

FIG. 6 is a detailed perspective view of the left side of the rollable and motorized door which is shown in FIG. 1;

FIG. 7 is a detailed perspective view of the right side of the rollable and motorized door which is shown in FIG. 1;

FIG. 8 is a detailed perspective view of the rolled sheet mounted on a mandrel of the rollable door shown in FIG. 1, the sheet including a lateral bulge;

FIG. 9 is a front view of the sheet of the rollable door in an unwound position, the lateral sides with the bulge of the sheet being inserted into an extrusion of a clip mounted on the vehicle shelter;

FIG. 10 is a top view of the unrolled sheet shown in FIG. 9; and,

FIG. 11 is a detail view from above of the left side of the sheet shown in FIG. 10, a right side of the sheet with the bulge being inserted into an extrusion of a clip mounted on the vehicle shelter shown in FIG. 10.

1 Claim, 9 Drawing Sheets
